UNITED STATES PATENT OFFICE.

LOUIS MAYER, LORENZ L. MAYER, AND EDWIN A. BYE, OF MANKATO, MINNESOTA,
ASSIGNORS TO MAYER BROTHERS COMPANY, OF MANKATO, MINNESOTA, A COR-PORATION OF MINNESOTA.

DESIGN FOR A TRACTOR-BODY.

53,508.

Specification for Design.

Patented July 8, 1919.

Application filed February 26, 1916. Serial No. 80,744. Term of patent 14 years.

To all whom it may concern:

Be it known that we, LOUIS MAYER, LORENZ L. MAYER, and EDWIN A. BYE, citizens of the United States, residing at Mankato, in the county of Blue Earth and State of Minnesota, have jointly invented a new, original, and ornamental Design for Tractor-Bodies, of which the following is a specification, reference being had to the accompanying drawing, forming part thereof.

The figure is a perspective view of a tractor body showing our new design.

Copies of this patent may be obtained for five cents each, by addressing the "Commissioner of Patents, Washington, D. C."

We claim:

The ornamental design for a tractor body, as shown.

LOUIS MAYER.
LORENZ L. MAYER.
EDWIN A. BYE.

Witnesses:

W. D. WILLARD,
F. G. BRADBURY.
